UNITED STATES PATENT OFFICE.

ZEGER JAN HENDRIK JONKER, OF KILVERSUM, NETHERLANDS.

HEAT-TRANSMITTING TUBE OF STEAM GENERATORS.

Application filed November 9, 1922, Serial No. 599,870, and in the Netherlands April 26, 1922.

The invention relates to improvements in water tubes for steam boilers, super heaters and the like and has for its object to increase the evaporative capacity, and to improve the water circulation, whereby the efficiency of the boiler may be considerably enhanced.

The known water tubes are usually closed hermetically at both ends and are partly filled with a liquid which serves as the means for transferring the heat. They project with their lower ends into the fire space or furnace, the upper parts of the tubes extending into the boiler.

The liquid contained in the water tubes is evaporated and the heat is transmitted to the water contained in the boiler. The liquid which is condensed in the upper part of the water tube flows down along the inner surface of the water tube until it reaches the lower part of the tube in which it is again heated. The condensed water consequently forms a cooling liquid layer which detrimentally affects the transmission of heat from the liquid or the generated steam to the water contained in the boiler. Moreover, the circulation of the water in the boiler is somewhat slow which prevents a high boiler efficiency from being obtained.

One construction of the improved boiler tube embodying the features of the invention is shown by way of example in the accompanying drawings in which:

Fig. 1 is a longitudinal section of a water tube and outer tube or jacket;

Fig. 2 is an elevation of the water tube and outer tube or jacket;

Fig. 3 is a top view and

Fig. 4 a longitudinal section of a water tube with flanges with circulation holes and outer tube or jacket and a water tube with flanges without outer tube or jacket;

Fig. 5 is a cross section on line 5-5 in Fig. 1;

Fig. 6 is a top view and

Fig. 7 a longitudinal section of a water tube with ribs.

Fig. 8 is a front view of the longitudinal slot at the juncture of the lower end of the return tube and the heat transmitting tube.

The improved water tube for boilers and the like comprises an inner tube and an outer tube or jacket. The inner tube is screwed or otherwise secured in the boiler bottom 1, the joint being hermetically sealed. The lower part 3 of the tube pro-

jects into the fire space or furnace 4, whilst the upper part 2 of the tube extends into the interior 5 of the boiler. The part 2 of the tube is, at its upper end, provided with a downwardly extending branch or extension 6 which communicates at its lower end with the lower end of the part 2. It will be seen from the drawings that the upper and lower ends of the tube 6 are gradually bent and open into the tube 2 at an angle α smaller than 90° . The port 7 through which the tube 6 communicates at its lower end with the tube 2 is in the form of a horizontal elongated slot in order to prevent the rising of the boiling water in tube 6.

The part 2 of the tube located in the interior boiler space 5, is provided with an outer jacket tube which consists of several independent coaxially arranged tubular sections 8, 9, and 10, each of which is closed at its lower end. Each jacket tube section 8, 9 and 10 is provided near its lower end with one or more openings 11, and its upper end with one or more openings 12, the water or steam entering the section through the lower opening or openings 11 and escaping through the top opening or openings 12. The uppermost outer tube section 10 is entirely open at the top and is moreover somewhat widened at the top to facilitate the escape of the steam into the steam space of the boiler.

The annular spaces between the outer tube sections 8, 9, and 10 and the inner tube part 2 are closed at the lower ends by bottom plates 13 in order to prevent the water from rising directly from one section into the next higher section of the outer tube. Direct passage of the water from one section into the next following is further prevented by laterally projecting extension plates 14 arranged above the exit openings 12.

The outer tube sections are held in alignment by means of centering projections 15 so that the tube sections are held coaxially with the inner tube.

Besides the tube parts 2 may be provided with flanges 18 constructed of some heat conducting material. In case outer tubes or jackets are used, the flanges 18 are to be provided with holes 16 or recesses. The flanges 18 may be substituted by ribs 17 arranged on the outer surface of the water tubes in a longitudinal direction.

The operation is as follows:

The liquid contained in the inner tube parts 3 and 2 is evaporated by the heat

transmitted in the furnace space 4 to the lower part 3. The steam or vapour contained in the upper part 2 of the tube transmits its heat to the boiler water contained in the space 5, is then condensed and returns through the return pipe 6 into the tube part 2. This return passage is located within the boiler space 5 so that the walls of the heat transmitting tube part 2 are not cooled by the condensed water. It will be understood that in this manner a very satisfactory transference of heat from the heated liquid or steam to the water contained in the boiler may be attained. The transference of heat is further assisted by the flanges 18 or ribs 17 and by the provision of the outer tubes which cause the boiler water to enter the annular spaces between the tube part 2 and the outer tube sections 8, 9 and 10 at different heights through the various openings 11 and enable the heated water to return to the boiler at different vertical points through the discharge openings 12. In this manner a very intensive and rapid water circulation within the boiler is effected, which increases the heat transmission coefficient and enables a very high thermal efficiency to be attained.

The improved jacketed boiler tubes enable a very high evaporation to be attained, about 90 kg. steam per square metre of heating surface, which in turn makes it possible to build boilers of this type for very high steam pressures.

35 **Claims:**

1. In apparatus of the class described, in combination, a furnace chamber; a boiler chamber; means separating said chambers; a sealed heat transmitting tube having its lower end located in said furnace chamber and its upper portion in said boiler chamber; and a return tube leading from the upper end of said heat transmitting tube to the lower end portion thereof, the lower end of said return tube communicating with said heat transmitting tube through a horizontal elongated opening at a point above said separating means.

2. In apparatus of the class described, in combination, a furnace chamber; a boiler chamber; means separating said chambers; a sealed heat transmitting tube having its lower end located in said furnace chamber and its upper portion in said boiler chamber; and a return tube leading from the upper end of said heat transmitting tube to the lower end portion thereof at a point above said separating means.

3. In apparatus of the class described, in combination, a furnace chamber; a boiler chamber; means separating said chambers; a plurality of sealed heat transmitting tubes having their lower ends located in said furnace chamber and their upper portions in said boiler chamber, each heat transmitting

tube being provided with a return tube leading from the upper end of said heat transmitting tube to the lower portion thereof at a point above said separating means.

4. In apparatus of the class described, in combination, a furnace chamber; a boiler chamber; means separating said chambers; a plurality of sealed heat transmitting tubes having their lower ends located in said furnace chamber and their upper portions in said boiler chamber; each heat transmitting tube being provided with a return tube leading from the upper end of said heat transmitting tube to the lower portion thereof at a point above said separating means, the lower end of said return tube joining said heat transmitting tube at an angle of less than 90°.

5. In apparatus of the class described, in combination, a furnace chamber; a boiler chamber; means separating said chambers; a plurality of sealed heat transmitting tubes having their lower ends located in said furnace chamber and their upper portions in said boiler chamber; each heat transmitting tube being provided with a return tube leading from the upper end of said heat transmitting tube to the lower portion thereof at a point above said separating means, and said return tube communicating with said heat transmitting tube through an elongated opening.

6. In apparatus of the class described, in combination, a furnace chamber; a boiler chamber; means separating said chambers; a sealed heat transmitting tube having its lower end located in said furnace chamber and its upper end in said boiler chamber and provided with a return tube leading from the upper end of said heat transmitting tube to the lower end portion thereof at a point above said separating means; a jacket surrounding said heat transmitting tube within the boiler chamber and provided with an entrance opening at its lower end and an exit opening at its upper end.

7. In apparatus of the class described, in combination, a furnace chamber; a boiler chamber; means separating said chambers; a sealed heat transmitting tube having its lower end located in said furnace chamber and its upper portion in said boiler chamber and provided with a return tube leading from the upper end of said heat transmitting tube to the lower end portion thereof at a point above said separating means; a sectional jacket surrounding said heat transmitting tube within said furnace chamber each section of said jacket being provided with a lower entrance opening and an upper exit opening.

8. In apparatus of the class described, in combination, a furnace chamber; a boiler chamber; means separating said chambers; a sealed heat transmitting tube having its

- lower end located in said furnace chamber and its upper portion in said boiler chamber and provided with a return tube leading from the upper end of said heat transmitting tube to the lower end portion thereof at a point above said separating means; a sectional jacket surrounding said heat transmitting tube within said furnace chamber each section of said jacket being provided with a lower entrance opening and an upper exit opening, the upper section of said jacket being flared at the top.
9. In apparatus of the class described, in combination, a furnace chamber; a boiler chamber; means separating said chambers; a sealed heat transmitting tube having its lower end located in said furnace chamber and its upper end in said boiler chamber and provided with a return tube leading from the upper end of said heat transmitting tube to the lower end portion thereof at a point above said separating means; a jacket surrounding said heat transmitting tube within the boiler chamber and provided with an entrance opening at its lower end and an exit opening at its upper end, and a baffle plate located above the exit opening of said jacket.
10. In apparatus of the class described, in combination, a furnace chamber; a boiler chamber; means separating said chambers; a sealed heat transmitting tube having its lower end located in said furnace chamber and its upper portion in said boiler chamber and provided with a return tube leading from the upper end of said heat transmitting tube to the lower end portion thereof at a point above said separating means; a sectional jacket surrounding said heat transmitting tube within said furnace chamber, each section of said jacket being provided with a lower entrance opening and an upper exit opening and a bottom plate for closing the lower end of each section.
11. In apparatus of the class described, in combination, a furnace chamber; a boiler chamber; means separating said chambers; a sealed heat transmitting tube having its lower end located in said furnace chamber and its upper end in said boiler chamber and provided with a return tube leading from the upper end of said heat transmitting tube to the lower end portion thereof at a point above said separating means; a jacket surrounding said heat transmitting tube within the boiler chamber and provided with an entrance opening at its lower end and an exit opening at its upper end; and centering means for said jacket.
- In testimony whereof I have signed my name to this specification.
- ZEGER JAN HENDRIK JONKER.
